Am Dyne Trust, a trust of Massachusetts

Filed May 20, 1957, Ser. No. 660,298

20 Claims. (Cl. 103—76)

This invention relates to an improved design of accelerator tube for use in fluid pumps of the types described in my copending application, Serial Nos. 553,015, filed December 14, 1955, now Patent No. 2,936,713; and 617,993, filed October 24, 1956, now Patent No. 2,948,225.

In pumps of the accelerator-tube type, flexible or semi-flexible tubes must be provided in order to form liquid-carrying transitions from the moving accelerator tube or tubes, to the stationary parts of the apparatus. In general, such flexible tubes may be made either of metal or of some plastic material. However, for many purposes, plastics are not suitable. For example, plastics will not withstand high internal temperatures and pressures. Hence, in many cases, metal tubing must be used. Whatever the mode of motion may be for the accelerator tube, its flexible connections to the stationary parts are subjected to mechanical stresses, due to the relative deflection between the stationary and moving ends, which increase in magnitude as the length of the flexible connection decreases. On the other hand, as the length of the connection increases, the fall of pressure in the internal liquid in the direction of the acceleration of the stream becomes greater. This pressure drop is always present whenever the liquid in the tube has an acceleration, and by the very nature of the pumping device, the internal liquid must have an alternating acceleration. The net result is that, while the accelerator tube imparts an acceleration to the liquid opposite to the direction of internal flow, and thereby creates a rise of pressure in the direction of flow, the concomitant acceleration of the liquid in the adjacent flexible connections is in the same direction as the flow therein, and thus causes a drop of pressure in the flow direction which must instantaneously detract from the rise of pressure in the accelerator tube, thus reducing the net alternating pressure difference which is available for external use beyond the hydraulic rectifying device.

Therefore the designer of a liquid pump of the accelerator-tube type is confronted with conflicting factors: he must make the length of the flexible connecting tubes as short as possible to minimize the internal pressure drop therein, but he must make these same tubes as long as possible in order to minimize the mechanical stresses in the walls of the tubes. He must also strive to make the effective length of the accelerator tube as long as possible relative to the total length of flexible tubes and any other static internal tubes (i.e. tubes lying on the alternating-flow side of the rectifying device), subject to certain very important restrictions which are discussed in what follows. It should be noted that it is possible, for a given external discharge of liquid, to reduce the acceleration of the liquid within the flexible tubes by simply increasing their internal cross-sectional area. However, this also raises the level of mechanical stresses in the walls of these tubes, and hence is not a solution to the problem. The limitations upon the extent to which the length of an accelerator tube can be increased exist because no liquid, and no tube which may contain this liquid, can

2

sustain internal pressure without an elastic deformation. In simple terms, the liquid is compressible, and the tube expandable, however slightly. This fact, together with the inertia of the liquid, necessitates a finite time delay in the transmission of pressure changes from one point to another in a liquid confined within an accelerator tube. Beyond a certain range of tube lengths, depending upon the properties of the liquid, the properties of the tube material, the dimensions of the tube, and the frequency of alternation of the tube velocity, an increase in the effective length of the accelerator tube no longer produces a proportional increase in the internal pressure rise, other factors remaining constant. This is so, in general terms, because the liquid in the tube cannot sustain a tensile stress, and must therefore be pushed by the trailing end of the accelerator tube; but as the length of the tube is increased, a longer time lapse is needed for this "push," or pressure impulse, to be propagated elastically along the liquid column to its other end. When this transit time for pressure impulses to travel the length of the tube becomes comparable to the period of the reciprocating motion of the tube, then the liquid within the tube no longer behaves like a lumped (i.e. perfectly rigid) body whose only important property is its total mass.

Accordingly, it is the principal object of the invention to provide an accelerator-tube-type pump designed not only to eliminate, or at least minimize, the aforementioned difficulties, but also to operate at relatively high frequencies, i.e., between 20 and 300 cycles per second, in an efficient and reliable manner. Further objects relate to features of design and will be better understood from a consideration of the following disclosure and the accompanying drawings which include explanatory figures and analogies as well as practical embodiments of the invention.

In the drawings:

Fig. 1 is an axial section through a simple form of accelerator tube having a length S_t and containing an isotropic liquid;

Fig. 2 is a view similar to Fig. 1, but presenting a mechanical analogy in which a series of pistons and compression springs replace the liquid;

Fig. 3 is a view showing an electrical analogue in the form of an alternating-current transmission line;

Fig. 4 is a view similar to Fig. 3, but showing an equivalent arrangement;

Fig. 5 is an elevation, with parts shown in section, of a practical embodiment of the invention;

Fig. 6 is an end elevation as seen along the line 6—6 of Fig. 5;

Fig. 7 is a section on the line 7—7 of Fig. 5;

Fig. 8 is a schematic view showing the hydraulic rectifier used with the system shown in Figs. 5 to 7;

Fig. 9 is an elevation, partly in section, of another embodiment of the invention; and

Fig. 10 is a schematic view showing the hydraulic rectifier used with the system shown in Fig. 9.

In accordance with the present invention my improved pump comprises one or more accelerator tubes which may be helical or rectilinear and one or both ends of the tube or tubes are connected with a hydraulic rectifier operative to produce a unidirectional external liquid flow in response to an oscillating fluid flow in the accelerator tube or tubes, as the case may be. The oscillating fluid flow in the accelerator tube or tubes may be induced mechanically or electrically, but the latter method is usually preferred because it is susceptible to a more accurate control of the amplitude of the oscillator. In the case of a helical accelerator tube torsional oscillations are required, but with a straight tube rectilinear oscillations are employed. For the reasons hereinafter con-

sidered the effective length of the tube, whether helical or rectilinear, should either approximate one-half the sonic wave length within the liquid as confined in the tube at the fundamental operating frequency, or any odd-integer multiple of this wave length. In order more fully to appreciate the fundamentals underlying the design of such accelerator-tube-type pumps, the considerations hereinafter set forth should be understood.

The design of accelerator-tube-type pumps presents a situation involving the propagation of sound waves through the liquid confined in the tube, and this phenomenon is susceptible to analysis, as shown in the subsequent discussion. By reference to any textbook on the theory of sound, it can be verified that the velocity of propagation of sound (or elastic waves) is given by the expression

$$v_o = \sqrt{\frac{E_w}{m}} \quad (1)$$

where

E_w =the adiabatic bulk modulus of compressibility of the liquid, (force)/(length)²;

m =the mass density of the liquid;

v_c =the velocity of sound in an infinite body of the liquid in question.

Note that Equation 1 gives only the sonic velocity in an infinite body of the liquid. When the liquid is confined within a metal tube, the velocity of sound in the axial direction of the tube is less than that in an infinite body of liquid, because the expansion of the tube wall has a physically identical effect to the compression of the liquid, the result being that the effective bulk modulus of compressibility of the liquid is reduced. For a thin-walled metal tube of circular cross section, which is long axially compared with its diameter, and which confines a homogeneous, isotropic liquid under some static pressure without voids or gas bubbles, the velocity of sound or elastic waves in the axial direction is given by

$$v'_o = \frac{v_o}{\sqrt{1 + \frac{E_w \cdot D_i}{E_t \cdot \delta_t}}} \quad (2) \quad 40$$

where

E_t =Young's modulus of elasticity for the tube material, (force)/(length)²;

E_w =the adiabatic bulk modulus of elasticity of the liquid, (force)/(length)²;

D_i =the inside diameter of the tube;

δ_t =the wall thickness of the tube;

v_c =the sonic velocity in an infinite body of the liquid, as given by Eq. 1, (length)/(time).

It is comparatively simple to derive an expression for the velocity of elastic waves in a liquid column confined within a tube having a cross section other than circular, but it is sufficient merely to state here that, other things being equal, a tube of circular cross section has the highest sonic velocity within its internal liquid. This is so because the perfect symmetry of the circular tube about its axis permits it to expand only in the "barrel-hoop" mode, which induces a pure tensile stress in the wall; whereas, a tube of non-circular cross section is subjected to outward bending of its walls, with the result that the increase of internal volume for each increment of internal pressure is greater than in the case of the circular tube. It should be noted that E_w is in general a function of both temperature and pressure, but this does not affect the validity of the analysis.

Consider Fig. 1, which shows a metal tube 1 of thin wall, long relative to its diameter, which confines under some pressure, and without voids, a homogeneous, isotropic liquid 2. The tube is closed and sealed at its ends. If this tube is subjected to an alternating rectilinear velocity, v_t , given by

$$v_t = \hat{v}_t \sin 2\pi ft, \quad t=\text{time} \quad (3)$$

parallel to its axis, and the frequency of alternation, f , in cycles per unit time, is sufficiently high that the sonic transit time in the tube is appreciable relative to $1/f$, then we must regard the internal liquid column as a continuous distribution of mass and compliance (the reciprocal of stiffness). We shall assume that longitudinal extension and compression of the tube itself are negligible, and that only radial expansion or contraction of the tube wall need be considered. If the natural frequency of the tube wall in this barrel-hoop mode of deformation is high relative to f , then the mass of the tube wall need not be considered, and the effect of the tube on the sonic velocity is given by Eq. 2. This is usually the case with metal tubes of thin wall. It is further assumed that the static internal pressure in the confined liquid is sufficiently high so that the symmetrical harmonic increase and decrease of pressure due to the elastic waves are always of lesser amplitude than this static pressure, and cavitation never occurs.

20 This continuous distribution of mass and compliance may be associated entirely with the liquid, for purposes of analysis, and the tube omitted from further consideration, if a new bulk modulus of compressibility for the liquid is defined as follows:

$$E'w = \frac{E_w}{1 + \frac{E_w \cdot D_i}{E_t \cdot \delta_t}} \quad (4)$$

where the various symbols are as previously defined.

30 Consider the situation as shown in Fig. 2, wherein the actual liquid has been replaced by a large number of identical, pure-mass pistons 3 which slide without friction inside the perfectly rigid metal tube 1 and are separated from one another by identical, pure-compliance compression springs 4. As the number of pistons and springs is increased, the situation of Fig. 2 becomes an increasingly better approximation to the situation of Fig. 1. The mass per unit length of this assembly is

$$\frac{M_w}{S_t} = \frac{m_w A_i S_t}{S_t} = m_w A_i \quad (5)$$

where

M_w =the total mass of the liquid column;

45 S_t =the total length of the liquid column;

A_i =the internal cross section of the tube, or

$$\frac{\pi D_i^2}{4}$$

50 m_w =the mass density of the liquid, (mass)/(volume). The compliance per unit length of the assembly in Fig. 2 is

$$\frac{1}{K'w} \cdot \frac{1}{S_t} = \frac{1}{E'w A_i} \quad (6)$$

55 where

$K'w$ =the total compressive stiffness of the liquid column in Fig. 1 (incl. tube expansion), or (applied force)/(decrease in length).

60 The following important observations concerning the assembly shown in Fig. 2 should be noted.

(1) Because the metal tube is much less compliant in the axial direction than is the liquid column or its equivalent array of pistons and springs, the ends of the tube and of the spring-and-piston column must have the same velocity at all instants of time;

65 (2) Because the ends of the tube have identical velocities, and because the spring-and-piston column is perfectly symmetrical about its axial center, the velocities of any pair of pistons symmetrically disposed relative to the center must be equal to each other; and

(3) The velocity of any piston lying between either end of the tube and the center is not equal to the velocity of the tube end.

The behavior of the system of Fig. 2 could be determined by direct solution of the basic differential equations for this case, but there is a much simpler method based upon the well known analogy suggested by Firestone, between mechanical and electrical systems. (See Firestone, F. A., The Mobility Method of Computing the Vibration of Linear Mechanical and Acoustical Systems: Mechanical-Electrical Analogies, Journal of Applied Physics, volume 9, No. 6, June, 1938.)

In the Firestone Analogy, the following primary variables are analogous: force~electric current, velocity~electro-motive force or potential difference, mass~capacitance, and compliance~inductance. By direct application of the Firestone Analogy to the system of Fig. 2, it can be demonstrated that its electrical analogue is the electrical transmission line shown schematically in Fig. 3. It should be noted, with reference to Fig. 2, that the following facts exist regarding Fig. 3:

(1) The potential difference between any point of the transmission line and its ground return is the analogue of the velocity relative to the earth of the corresponding piston in Fig. 2.

(2) The electric current flowing in the transmission line at any point is the analogue of the total force (pressure times area) transmitted by the corresponding spring of Fig. 2.

(3) The generator end, or sending end, of the transmission line is connected by a zero-impedance bus bar to the receiving end of the line, so that the potential differences of these ends relative to ground are always the same.

(4) The series inductance per unit length of the transmission line is the analogue of the compliance per unit length of Fig. 2.

(5) The shunt capacitance per unit length of line in Fig. 3 is the analogue of the mass per unit length of Fig. 2.

(6) The plus and minus signs of Fig. 3 indicate that the associated potential difference is to be considered instantaneously positive when it has that polarity.

(7) The arrows associated with current symbols in Fig. 3 indicate the positive direction for instantaneous electric currents.

(8) The generator attached to the sending end of the transmission line in Fig. 3 is a source of sinusoidal alternating current and potential difference, and corresponds to the mechanism (not shown), which produces the sinusoidal tube velocity in Fig. 2.

Because of the bus bar connecting the ends, and the symmetry of the transmission line about its center, it is clear that points on the line which are symmetrically disposed relative to the center must have identical currents and potential differences relative to ground. Hence the transmission line of Fig. 3 is exactly equivalent to the transmission line of Fig. 4, which has half the length of the line in Fig. 3, twice the shunt capacitance per unit length, and half the series inductance per unit length. The receiving end of the new line of Fig. 4 corresponds to the midpoint of the line in Fig. 3.

Since the theory of lossless electrical transmission lines has been firmly established for many years, the equations for the potential difference and current at any point on the line of Fig. 4 may be stated, without giving a formal derivation. It is to be noted that losses have been neglected in the transmission line because the frictional forces in the original tube of Fig. 1 are negligibly small compared with the inertial forces.

If distance be measured from the receiving end of the equivalent transmission line of Fig. 4, then the potential difference at the sending end of the line is given by

$$\bar{V}_t = \bar{V}_r \cos \frac{\pi f S_t}{v'_c} \quad (7)$$

where

$\bar{V}_t$ =the complex algebraic expression for the sending-end potential difference to ground;

$\bar{V}_r$ =the complex algebraic expression for the receiving-end potential difference to ground;

v'_c =the velocity of propagation of electromagnetic waves on the transmission line, numerically equal to the sonic velocity in the liquid column in Fig. 1;

f =the frequency of alternation of potential difference and current on the line, numerically equal to the frequency of velocity alternation for the tube of Fig. 1;

S_t =the total length of tube in Fig. 1 or Fig. 2, or twice the length of the equivalent transmission line in Fig. 4.

10 15 The electric current at the sending end of the line in Fig. 4 is given by

$$\bar{I}_t = j Y_c \bar{V}_r \sin \frac{\pi f S_t}{v'_c} \quad (8)$$

20 where

$\bar{I}_t$ =the complex algebraic expression for the sending-end current;

$\bar{V}_r$ =the complex expression for the receiving-end potential difference;

Y_c =the characteristic admittance (a pure real number) of the line in Fig. 4;

j =the complex operator which signifies a phase advance of 90 electrical time degrees.

30 35 For the significance of complex quantities as applied to simple harmonic functions, consult any basic text on the theory of alternating-current circuits.

In general, the characteristic admittance of a line is defined as the square-root of the ratio of shunt capacitance per unit length to series inductance per unit length. Hence, for the line in Fig. 4, we have

$$Y_c = 2 \sqrt{\frac{C_w}{L'_w}} \quad (9)$$

40 where

C_w =the shunt capacitance of the entire line in Fig. 3;

L'_w =the total series inductance of the line of Fig. 3.

45 50 In order to express Y_c in terms of the mechanical parameters of Figs. 1 and 2, the following fundamental identities which relate mechanical to electrical variables in the Firestone Analogy are used:

$$C_w = \frac{M_w}{U^2} = \frac{m A_i S_t}{U^2} \quad (10)$$

where

U^2 =the square of the arbitrary transduction constant, U , which is the ratio of (force)/(current) or of (potential difference)/(velocity).

55 55 M , A_i and S_t have been previously defined.

$$L'_w = \frac{U^2}{K'_w} = \frac{U^2 S_t}{E'_w A_i} \quad (11)$$

60 65 where S_t , E'_w , A_i , and U are as previously defined.

Substitution of the expressions of (10) and (11) into Eq. 9, gives

$$Y_c = \frac{2 A_i}{U^2} \sqrt{E'_w m} \quad (12)$$

The electrical impedance seen by the generator looking into the sending end of the transmission line of Fig. 4

70 75 is the ratio of the sending-end potential difference to the sending-end current:

$$\bar{Z}_t = \frac{\bar{V}_t}{\bar{I}_t} = \frac{-j}{Y_c \tan \frac{\pi f S_t}{v'_c}} = \frac{-j U^2}{2 A_i \sqrt{m E'_w} \tan \frac{\pi f S_t}{v'_c}} \quad (13)$$

where

$\bar{Z}_t$ = the complex expression for the sending-end impedance of the transmission line of Fig. 4.

In view of the fundamental identities of the Firestone Analogy regarding force and velocity,

$$\bar{F}_t = U \bar{I}_t \quad (14)$$

$$v_t = \frac{\bar{V}_t}{U} \quad (15)$$

where

$\bar{F}_t$ = the complex algebraic expression for the sinusoidally varying force exerted by the tube of Fig. 1 or Fig. 2 on either end of the internal column;

v_t = the complex algebraic expression for the velocity of the tube in Fig. 1 or Fig. 2.

It follows that Equation 13 expresses the complex ratio of velocity to force at either end of the tube in Figs. 1 and 2:

$$\frac{\bar{v}_t}{\bar{F}_t} = \frac{\bar{V}_t}{\bar{I}_t} \frac{1}{U^2} = \frac{-j}{2A_1 \sqrt{m E'_{\infty}} \tan \frac{\pi f S_t}{v'_c}} \quad (16)$$

Equation 16 leads to a very important conclusion. It is clear that the quantity

$$\tan \frac{\pi f S_t}{v'_c}$$

in the denominator of the right-hand side of (16) is a function of the frequency, f , since the sonic velocity, v'_c and the tube length, S_t , are given. In particular, if the frequency has the critical value

$$f_c = \frac{v'_c}{2S_t} \quad (17)$$

then

$$\tan \frac{\pi f S_t}{v'_c} \rightarrow \infty \quad (18)$$

and the ratio $\bar{v}_t/\bar{F}_t$ becomes zero. The significance of this, physically, is that the liquid column inside the tube of Figs. 1 and 2 undergoes an internal resonance which makes it a vibration absorber, with the ends of the liquid column remaining motionless against any finite force which the metal tube is capable of exerting.

Under the conditions of Equations 17 and 18, the reactions of the ends of the liquid column against the end walls of the tube are exactly those which would occur if the liquid column were replaced by a tight-fitting solid rod of infinite mass and stiffness.

It should be noted, that when the frequency has the critical value given by Equation 17, the center of the actual liquid column in Fig. 1 does have a finite velocity and zero dynamic alternation of pressure or total force, although the ends of the column have zero velocity against a finite alternating force.

The criterion of Equation 17 may be expressed in a slightly different way which is more instructive in case the operating frequency, f is fixed, and the length of the tube can be chosen at will. The velocity of propagation of sound waves in the liquid column confined within the tube is related to the frequency of the pressure changes by the equation

$$\frac{v'_c}{f} = \Delta'_c \quad (19)$$

where

Δ'_c = the wave length of a sound wave in the liquid confined within the tube at the frequency f .

By means of Equation 19, we may rewrite (17) in the form

$$S_t = \frac{\Delta'_c}{2} \quad (20)$$

Thus, the liquid column in the tube becomes a vibration absorber when the total length of the column is equal to half a sonic wave length at the operating frequency.

By means of an extension of the foregoing analysis, it can be demonstrated that the following things are true regarding the tube of Figs. 1 and 2:

(1) When the total length of the tube is an odd-integer multiple of half a sonic wave length at the operating frequency, the liquid column behaves at its ends like a vibration absorber.

(2) When the total length of the tube is any even-integer multiple of half a sonic wave length at the operating frequency, then the liquid column permits any finite velocity at its ends and will sustain no alternating force or pressure there.

The importance of the foregoing facts in the design of accelerator tubes becomes evident. If the tube of Fig. 1 is now open at its ends, and connected to flexible tubes of the same inside diameter, wall thickness, etc., which

introduce a change in the stream direction of approximately 90° at each end of the tube, then there is produced an accelerator tube of the type suitable for pumps like those described in my copending applications. The liquid column within the straight accelerator tube now is no longer pushed by the ends of this tube, but rather is pushed by the ends of the liquid columns in the adjacent flexible connections. The behavior of the inner liquid column is still the same as before, however. Hence if the length of the flexible connections is sufficiently short

that they may be regarded as lumped hydraulic elements, the liquid column within the accelerator tube proper can be made to behave like a frictionless piston of infinite mass, provided only that the length of the accelerator tube is half a sonic wave length in the liquid column as

confined by this tube at the fundamental operating frequency, or any odd-integer multiple of this length. It is not essential that the waveform of the force applied to the ends of the liquid column be a pure sinusoid of the fundamental frequency; any complex waveform of end force

or pressure which contains only odd Fourier harmonics of the base frequency will cause the liquid column within the accelerator tube to behave in the same manner. Such Fourier spectra are actually encountered in many cases of practical application of accelerator-tube pumps.

It should be noted that it is undesirable that the length of the accelerator tube be any even-integer multiple of half the sonic wave length, because then the inner liquid column behaves like a liquid piston of zero effective mass, and the pump becomes inoperable.

In view of the foregoing considerations, the novel features and advantages of my invention will now be apparent. It provides, within a compact structure, an accelerator tube which has a length exactly equal to half the sonic wave length in the confined liquid at the operating frequency, and flexure tubes (flexible extensions) which have short effective hydraulic lengths and long effective mechanical lengths. Furthermore, the entire liquid circuit through this assembly rises continuously from the bottom end to the top end, with no high spots, pockets, or domes which can trap air or other gases internally. It

is essentially a helix of tube mechanically supported upon vertical axial extensions of this tube, and driven in a torsional oscillation by means of two electrodynamic vibration motors tangentially connected to the helix of tube at opposite ends of a diameter of the structure.

Referring to Figs. 5 to 8, the pump shown therein is designed to operate in conjunction with two other identical units at frequencies between approximately 20 and 300 cycles per second. Each unit is rigidly supported in a suitable frame (not shown) by upper and lower flange fittings 1 and 2. The upper flange 1 is welded or otherwise suitably connected with the upper end of a rigid metal outer tube 4, the lower end of which is connected by a circular ring 5 of T-shape cross section with the lower end of an intermediate rigid metal tube 6. The

upper end of the intermediate tube is connected by another circular ring 8 of T-shape cross section with a rigid metal inner tube 10, and the lower end of the inner tube is connected to a heavy-wall pipe or coupling 12.

In a similar manner the lower flange 2 is connected with an inner tube 14 which is connected by ring 15 to an intermediate tube 16 and the latter is connected by a ring 18 with an outer tube 20. The upper end of the outer tube is connected with a heavy-wall pipe or coupling 22 corresponding to the coupling 12. The assemblies 4 to 10 and 14 to 20 to provide telescopic torsion tubes having an effective mechanical (twisted) length of approximately three times that of any individual constituent tube.

The lower end of the upper coupling 12 and the upper end of the lower coupling 22 are provided with flanged metal plugs 24 and 25 (Fig. 7) which fit a hollow central hub 26, thus providing a rigid connection between the telescopic-torsion-tube assemblies. The upper end of the plug 24 and the lower end of the plug 25 are truncated at a 45° angle and opposite their truncated portions the couplings 12 and 22 are provided with circular openings which receive the upper and lower extensions 28 and 30 of a helical coil 32 of metal tubing of circular cross section, it being understood that the parts are welded, brazed or otherwise suitably secured to provide leakproof joints.

The helix 32 is closely coiled and has its adjacent turns welded to one another at suitably spaced points along the inner and outer surfaces of the helix and the effective length of this helix along its tubular axis is one-half the sonic wave length at the operating frequency. Longitudinally extending metal struts 34 and 36 are welded to diametrically opposite sides of the inner face of the helix and the ends of these struts are provided with circular flanges against which two pairs of thin metal shear plates 38 and 40 are disposed, the plates being separated by compression washers 42 and 44. Nuts 45 and 46 carried by the threaded ends of the struts hold the shear plates and washer assemblies tightly to the ends of the struts.

The centers of the shear plates are separated by large compression washers 48 and 50 which are circumscribed about the tubes 10 and 20 and these compression washers are bolted to the flanged ends of the couplings 12 and 22. Although the natural frequency of the helix assembly and the torsional stiffness of the tube assemblies are to some extent under the designer's control, the stiffness is likely to be rather high, necessitating the addition of an excess moment of inertia over and above that which is inherent in the helix assembly, and in order to achieve this a split flywheel 52 is clamped about the hub 26 so that the natural frequency of the helix assembly is equal to the driving frequency of the vibrator.

The vibrators are preferably of the electrodynamic type where relatively high frequencies are used, and as shown in Fig. 6, the vibrator comprises a pair of rectilinear electrodynamic vibration motors 55 and 56 which are rigidly secured to the supporting frame (not shown), these motors having the general construction shown in my copending application Serial No. 553,015, filed December 14, 1955. The armature coils 58 and 60 of the motors are electrically connected to produce equal and opposite forces which are transmitted tangentially to the lower end of the helix assembly by flexible drive links 62 and 64. These links are so designed that they are rigid in their axial direction, but somewhat resilient in transverse bending so as to allow for slight misalignment of the vibration motors relative to the helix assembly. The forces produced by the vibration motors constitute a couple, or pure torque, which causes the helix assembly to undergo a torsional oscillation about its own axis.

Although the unit above described is capable of operating alone, as disclosed in my copending application Serial No. 553,015, it may be used in a three-phase or other polyphase system. As shown schematically in Fig. 8, the tubes 14, 14a and 14b of the helices 32, 32a and 32b are interconnected, and the upper tubes 4, 4a and 4b are

connected with the three-phase hydraulic rectifier which is preferably of the type shown in my copending application Serial No. 636,597, filed January 28, 1957, now abandoned. Such a hydraulic rectifier is schematically represented by three pairs of check valves, using the electrical symbols, and one check valve of each pair is connected to the intake line 70 and the other to the discharge line 72.

The operation is as described in my aforementioned copending application Serial Nos. 553,015 and 636,597, and combines the three advantages, namely, a half-sonic-wave-length accelerator tube, a short hydraulic length of flexible tube at each end, and a comparatively large length of mechanically twisted tube. A further advantage is that the construction is such as to be self-purging of trapped and entrained gases.

In Fig. 9 I have shown a single unit pump designed to operate at frequencies up to approximately 30 cycles per second and although it is here shown as being operated by electrodynamic vibrators, it is to be understood that any other mechanism may be used to produce the desired operating frequency. Except for the telescopic torsional tubes which have been replaced by the hydraulic rectifiers and flexible connecting hoses, the operating parts are identical to those of unit shown in Figs. 5 to 7. Accordingly, the same reference characters designate corresponding parts.

In this embodiment the upper end of the coupling 12 is connected with a rigid pipe 80 and the lower end of the coupling 22 is connected with a rigid pipe 82. These pipes fit within the inner races of ball bearings 84 and 85 which are bolted to the inner horizontal frame members 86 and 87. Mounted within the space between the inner and outer horizontal frame members 86 and 88 is a rectifying unit 90 comprising a housing 91 having a horizontal partition 92 and a vertical partition 93 defining the chambers 94, 95 and 96. The pipe 80 is connected with the chamber 96 which in turn is connected with the chambers 94 and 95, there being spring-loaded ball checks 97 and 98 secured to the horizontal partition 92. The undamped natural frequency of the check-spring-and-ball assemblies is at least twice the frequency of the velocity variation of the propellant liquid in the accelerator tube 32, as explained more fully in my copending application Serial No. 636,597. The ball check 97 permits liquid surges to pass only from the chamber 96 into the chamber 95 and the ball check 98 permits liquid surges to pass only from chamber 94 to chamber 96. The chambers 94 and 95 are separated by the partition 93 and these chambers have ports 100 and 101 which are respectively connected to heavy fatigue-resistant flexible tubes 102 and 103 which may be of rubber or other suitable material.

Mounted within the space between the inner frame member 87 and the outer frame member 105 is another rectifying unit 90a identical with the unit 90 to which similar reference characters are applied to corresponding parts. The heavy flexible tubes 102a and 103a, as well as the tubes 102 and 103, are connected with the exterior circuit, as schematically shown in Fig. 10, wherein the tubes 102 and 103a are connected to the delivery duct 105 which runs to the receiver 106, and the tubes 103 and 102a are connected with the return line 108.

In operation the amplitude of the torsional movement of the helix 32 is much greater than in the previously described embodiment and this is permitted because of the flexible tubes 102, 102a, 103 and 103a, the inner ends of which oscillate in an arcuate path while their outer ends remain fixed to the frame members 88 and 105. In all other material particulars the operation is as set forth in my aforementioned copending applications. Because the torsional stiffness of the flexible tubes 102, 102a, 103 and 103a is likely to be rather low, it may be unnecessary to use the flywheel 52. In fact, it may be necessary to add more torsional stiffness in order to

make the natural frequency of the unit equal to the driving frequency.

It is to be understood that this disclosure is for the purpose of illustration and that various changes and modifications may be made without departing from the spirit and scope of the invention as set forth in the appended claims.

I claim:

1. A pump comprising a generally annular member having end portions and providing an accelerator tube containing a propellant liquid, means for imparting to said accelerator tube a rotary oscillatory movement so as to produce an alternating flow therein, the length of said tube being approximately one-half an odd integer multiple of the wave length of sound within the liquid in the tube at the fundamental operating frequency, ducts connected with the end portions of said accelerator tube so as to provide an inlet and a discharge, a rectifier means connected with said ducts so that a unidirectional flow is produced in said discharge in response to an alternating flow in said accelerator tube. 10

2. A pumping unit comprising an accelerator tube containing a liquid, means for vibrating said tube at a predetermined frequency so as to produce an oscillating liquid flow therein, said tube being substantially non-deformable in the direction extending along its longitudinal axis, the length of said tube and thus the liquid column contained therein being approximately one-half an odd integer multiple of the wave length of sound within the liquid in the tube at the fundamental operating frequency, and hydraulic rectifying means connected with said tube so that a unidirectional discharge is produced in response to an oscillating flow in said tube. 20

3. A pumping unit comprising a coiled accelerator tube containing a liquid, means for imparting a rotary oscillatory movement of predetermined frequency to said tube so as to produce an oscillating liquid flow therein, the axial length of said tube being approximately one-half an odd integer multiple of the wave length of sound within the liquid in the tube at the fundamental operating frequency, and hydraulic rectifying means connected with said tube so that a unidirectional discharge is produced in response to an oscillating flow in said tube. 30

4. A pumping unit comprising an accelerator tube containing a liquid, means for vibrating said tube at a frequency of at least twenty cycles per second so as to produce an oscillating liquid flow therein, said tube being substantially non-deformable in the direction extending along its longitudinal axis, the length of said tube and thus the liquid column contained therein being approximately one-half the wave length of sound within the liquid in the tube at the fundamental operating frequency, and hydraulic rectifying means connected with said tube so that a unidirectional discharge is produced in response to an oscillating flow in said tube. 40

5. A pumping unit comprising a coiled accelerator tube containing a liquid, means for imparting a rotary oscillating movement of at least twenty cycles per second to said tube so as to produce an oscillating liquid flow therein, the axial length of said tube being approximately one-half the wave length of sound within the liquid in the tube at the fundamental operating frequency, and hydraulic rectifying means connected with said tube so that a unidirectional discharge is produced in response to an oscillating flow in said tube. 50

6. In a pumping system adapted to be connected with an exterior circuit having a delivery line and a return line, a pump unit comprising an accelerator tube containing a liquid, means for vibrating said tube at a predetermined frequency so as to produce an oscillating liquid flow therein, said tube being substantially non-deformable in the direction extending along its longitudinal axis, the length of said tube and thus the liquid column contained therein being approximately one-half an odd integer multiple of the wave length of sound within the liquid in the tube at the fundamental operating frequency, and hydraulic rectifying means connected with said tube so that a unidirectional discharge is produced in response to an oscillating flow in said tube. 60

liquid in the tube at the fundamental operating frequency, and hydraulic rectifier means connected with said tube and with the delivery and return lines so that a unidirectional flow takes place in the delivery line in response to an oscillating flow in said tube. 5

7. In a pumping system adapted to be connected with an exterior circuit having a delivery line and a return line, a pump unit comprising a helical accelerator tube containing a liquid, means for imparting to said tube a rotary oscillatory movement of predetermined frequency so as to produce an oscillating liquid flow therein, the length of said tube being approximately one-half an odd integer multiple of the wave length of sound within the liquid in the tube at the fundamental operating frequency, and hydraulic rectifier means connected with said tube and with the delivery and return lines so that a unidirectional flow takes place in the delivery line in response to an oscillating flow in said tube. 15

8. A pump unit comprising a helical accelerator tube containing a liquid, a cylindrical supporting member coaxial with said tube, coupling means at the opposite ends of said supporting member, means connecting the opposite ends of said tube with said coupling means, means for imparting a rotary oscillatory movement of predetermined frequency to said tube so as to produce an oscillating liquid flow therein, the axial length of said tube being approximately one-half an odd integer multiple of the wave length of sound within the liquid in the tube at the fundamental operating frequency, and hydraulic rectifier means connected with said coupling means so that a unidirectional discharge is produced in response to an oscillating flow in said tube. 25

9. A pump unit comprising a helical accelerator tube containing a liquid, a cylindrical supporting member coaxial with said tube, coupling means at the opposite ends of said supporting member, means connecting the opposite ends of said tube with said coupling means, means for imparting a rotary oscillatory movement of predetermined frequency to said tube so as to produce an oscillating liquid flow therein, the axial length of said tube being approximately one-half an odd integer multiple of the wave length of sound within the liquid in the tube at the fundamental operating frequency, a flywheel secured to said supporting member between said coupling means, and hydraulic rectifier means connected with said coupling means so that a unidirectional discharge is produced in response to an oscillating flow in said tube. 30

10. A pump as set forth in claim 9, wherein said flywheel is so constructed that its moment of inertia can be varied. 45

11. A pump unit comprising a helical accelerator tube containing a liquid, a cylindrical supporting member coaxial with said tube, coupling means secured to the opposite ends of said supporting member, means connecting the opposite ends of said tube with said coupling means, means for imparting a rotary oscillatory movement of predetermined frequency to said tube so as to produce an oscillating liquid flow therein, the axial length of said tube being approximately one-half an odd integer multiple of the wave length of sound within the liquid in the tube at the fundamental operating frequency, flexible tubes connected with said coupling means, said flexible tubes being capable of undergoing a torsional movement, and hydraulic rectifier means connected with said flexible tubes so that a unidirectional discharge is produced in response to an oscillating flow in said accelerator tube. 50

12. A pump unit comprising a helical accelerator tube containing a liquid, a cylindrical supporting member coaxial with said tube, coupling means at the opposite ends of said supporting member, means connecting the opposite ends of said tube with said coupling means, struts secured to the convolutions of said tube at diametrical opposite points, means acting on said struts for imparting a rotary oscillatory movement of predetermined frequency so as to produce an oscillating liquid flow in said tube. 60

tube, the axial length of said tube being approximately one half an odd integer multiple of the wave length of sound within the liquid in the tube at the fundamental operating frequency, and hydraulic rectifier means connected with said tube so that a unidirectional discharge is produced in response to an oscillating flow in said tube.

13. A pump unit comprising a helical accelerator tube containing a liquid, means for imparting a rotary oscillatory movement of predetermined frequency to said tube so as to produce an oscillating liquid flow therein, the axial length of said tube being approximately one half an odd integer multiple of the wave length of sound within the liquid in the tube at the fundamental operating frequency, and a torsion tube assembly including a plurality of spaced telescopically disposed tubes having interconnected end portions, said torsion tube assembly being connected at one end with one end of said accelerator tube and having means at its other end for rigidly mounting said other end to a frame and the like.

14. A pump unit comprising a helical accelerator tube containing a liquid, means for imparting a rotary oscillatory movement of predetermined frequency to said tube so as to produce an oscillating liquid flow therein, the axial length of said tube being approximately one half an odd integer multiple of the wave length of sound within the liquid in the tube at the fundamental operating frequency, and a pair of torsion tube assemblies each including a plurality of spaced telescopically disposed torsion tubes having interconnected ends, said pair of torsion tube assemblies being respectively connected at one end with the opposite ends of said accelerator tube and having means at their other ends for rigidly mounting said other ends to a frame and the like.

15. A pump unit comprising a helical accelerator tube containing a liquid, a cylindrical supporting member coaxial with said tube, coupling members at the opposite ends of said supporting member, means connecting the opposite ends of said tube with said coupling members, means for imparting a rotary oscillatory movement of predetermined frequency to said tube so as to produce an oscillating liquid flow therein, the axial length of said accelerator tube being approximately one half an odd integer multiple of the wave length of sound within the liquid in the tube at the fundamental operating frequency, and a pair of torsion tube assemblies each including a plurality of spaced telescopically disposed torsion tubes having interconnected ends, said assemblies being respectively connected at one end with said coupling members and having means on their other ends for rigidly mounting said other ends to a frame and the like.

16. A pump as set forth in claim 15 wherein a flywheel is mounted on said cylindrical supporting member between said coupling members.

17. A pump unit comprising a helical accelerator tube containing a liquid, a cylindrical supporting member coaxial with said tube, coupling members at the opposite ends of said supporting member, means connecting the opposite ends of said tube with said coupling members, means for imparting a rotary oscillatory movement of predetermined frequency to said tube so as to produce an

oscillating liquid flow therein, the axial length of said accelerator tube being approximately one half an odd integer multiple of the wave length of sound within the liquid in the tube at the fundamental operating frequency, hydraulic rectifiers connected with said coupling members, said rectifiers having intake and discharge ports, and interconnected flexible tubes connected with the intake and discharge ports so that a unidirectional flow is produced in said discharge ports in response to an oscillating flow in said accelerator tube.

18. A pump comprising a generally annular member having end portions and providing an accelerator tube containing a propellant liquid, means for imparting to said accelerator tube a rotary oscillatory movement so as to produce an alternating flow therein, the length of said tube being approximately one-half an odd integer multiple of the wave length of sound within the liquid in the tube at the fundamental operating frequency, coaxial ducts connected with the end portions of said accelerator tube so as to provide an inlet and a discharge, and rectifier means connected with said ducts so that a unidirectional flow is produced in said discharge in response to an alternating flow in said accelerator tube.

19. A pump comprising a generally annular member providing an accelerator tube having a pair of ends and containing a propellant liquid, means for imparting to said accelerator tube a rotary oscillatory movement so as to produce an alternating flow therein, a duct capable of undergoing torsional oscillatory movement connected to one end of said tube, and rectifier means interposed between said duct and the end of said accelerator tube, said rectifier means having intake and discharge ports and check valves operative to produce a unidirectional flow through the discharge port in response to an alternating flow in said accelerator tube.

20. A pump comprising a generally annular member having end portions and providing an accelerator tube containing a propellant liquid, means for imparting to said accelerator tube a rotary oscillatory movement so as to produce an alternating flow therein, inlet and discharge ducts connected with the end portions of said accelerator tube, said ducts being coaxial with said accelerator tube and with each other, at least one of said ducts being capable of undergoing torsional oscillatory movement, and rectifier means connected with said ducts so that a unidirectional flow is produced in said discharge duct in response to an alternating flow in said accelerator tube.
